UNITED STATES PATENT OFFICE

146,601

DESIGN FOR A TEMPLE FOR SPECTACLES

Bernice Jaffe, Chicago, Ill.

Application February 12, 1947, Serial No. 136,855

Term of patent 14 years

(Cl. D57—1)

To all whom it may concern:

Be it known that I, Bernice Jaffe, a citizen of the United States, residing at Chicago, in the county of Cook and State of Illinois, have invented a new, original, and ornamental Design for a Temple for Spectacles, of which the following is a specification, reference being had to the accompanying drawing, forming part thereof.

Figure 1 is a side elevational view of a temple for spectacles, showing my new design.

Fig. 2 is a top plan view of the same.

Figs. 3 and 4 are enlarged cross-sectional views thereof taken on the lines 3—3 and 4—4 of Fig. 1 respectively.

Fig. 5 is an enlarged cross-sectional view thereof taken on the line 5—5 of Fig. 2.

I claim:

The ornamental design for a temple for spectacles, as shown.

BERNICE JAFFE.
